INSULATED POTENTIAL COILS

Richard A. Road, West Lafayette, Ind., assignor, by mesne assignments, to Duncan Electric Company, Inc., Lafayette, Ind., a corporation of Indiana

Application May 18, 1953, Serial No. 355,578

3 Claims. (Cl. 317—158)

In some forms of electromagnetic structures, the provision of adequate insulation between the coil and the core around which it is wound presents a problem of both importance and difficulty. For example, in watt-hour meters, a laminated core structure has a longitudinal portion extending through the coil, and transverse portions extending laterally beyond the ends of the coil. For reasons of economy and electrical efficiency, it is desirable to have the coil fit the core portion within it as closely as is practicable, and extend close to the transverse portions thereof. According to common practice, the coils are wound on paper tubes designed to slide fairly snugly over the core. The tube insulates the coil from the core except at the ends. If there were room to extend the tube sufficiently beyond the ends of the coil, the insulation at the ends would be adequate, too, but such is not the case. A separate body of insulation can be placed between the ends of the coil and the radially extending core portions, but between this separate body and the tube there would be a short path between the coil and the core along which creepage or arcing could occur. Creepage is the flow of current along the surface of the insulating material, a phenomenon which can occur under some conditions of dampness. For some purposes, it is preferred that the end insulating material be a molded material. It is especially important to prevent creepage along such materials, because the creepage currents carbonize the material and make it conductive so that the material itself carries current. This in turn makes more of the material conductive and this cumulative effect can be quickly disastrous.

Although several ways have been developed for overcoming the creepage danger, they are relatively troublesome or expensive, or require special materials which it is not always desirable to use. According to the present invention, the minimum creepage distance is increased to a satisfactory length at little or no extra cost. When the laminations are stamped, the core portion is made slightly narrower by shallow recesses in the vicinity of the places over which the coil ends will lie. When the core is assembled and the coil applied thereto, the molded insulation, applied as it would have been applied anyway, flows into the shallow depressions provided by the notches in the laminations and thus overlaps the ends of the tube enough to provide the required minimum creepage distance. Along the flat faces of the laminations, the insulation also flows a short distance under the tube, the space in this instance being provided by insertion of a spacer shorter than the tube. Thus there is provided a satisfactorily dependable insulation, even though the coil is long enough to extend very close to the transverse portions of the core structure.

Additional objects and advantages of the invention will be apparent from the following description and from the drawings.

Designation of figures

Fig. 1 is a perspective view of the potential coil portion of a driving element of a watt-hour meter, partly

2

broken away to show features of this invention in cross section.

Fig. 2 is a face view of one of the laminations of Fig. 1.

5 Fig. 3 is a fragmentary view of the structure of Fig. 1, showing a section through the coil and insulation parallel to the face of a lamination.

Fig. 4 is a fragmentary view of the structure of Fig. 1, showing a cross section through the coil and insulation 10 along a plane perpendicular to the faces of the laminations.

Although the law requires a full and exact description of at least one form of the invention, such as that which follows, it is, of course, one purpose of a patent to cover 15 each new inventive concept therein no matter how it may later be disguised by variations in form or additions of further improvements; and the appended claims are intended to accomplish this purpose by particularly pointing out the parts, improvements, or combinations in which 20 the inventive concepts are found.

General description

The embodiment of the invention chosen for illustration includes a stack 11 of laminations 12. A coil 13 extends around the longitudinal core portion 14 of the lamination. The space provided for the coil is limited lengthwise of the core portion 14 by transversely extending portions 16 and 17 of the laminations.

So that a given number of turns of wire of a given size 30 can be carried around the central core 14 with a minimum average length of turn in the coil 13, it is desirable for the axial length of the coil to be almost as great as the spacing between the transverse portions 16 and 17. The minimum average length of the turns provides 35 a coil of the minimum electrical resistance and therefore greater electrical efficiency, and also reduces the cost of the coil because less copper is used. Furthermore, in some instances it might be necessary to extend the coil 13 quite close to the transverse portions 16 and 17 because there would not otherwise be room within the total space provided for the required number of turns and the necessary surrounding insulation.

The present invention is concerned with providing adequate insulation between the laminations and the coil 45 which lies close to the laminations. Coil 13 is conventionally wound on a tube 18 of insulating material such as a suitable paper. The problem of insulation is especially severe when the portions of the coil adjacent the ends of the tube 18 are closer to the laminations than 50 the acceptable minimum creepage distance. Under these circumstances, it becomes necessary to so dispose the insulation that current flowing from the coil to the laminations would have to take a longer path than the minimum acceptable creepage distance. When molded insulation 19 is used, this longer path can be provided by having the molded insulation extend in between the tube 18 and the main core portion 14, as seen at 21.

Insulation flowed along faces

60 Along the faces of the stacked laminations, it is practical to provide space for the insulation to flow along the faces by inserting a wedge 22, preferably formed of insulating material such as vulcanized fiber between the tube 18 and the laminations 12. Such a wedge is desirable in any event so that the coil will be more firmly mounted on the core. It should be understood that according to ordinary manufacturing practice, the coil is wound on a tube preliminarily, and then applied to the core (the laminations being flexed and slipped into 65 place) so that the coil is initially slightly loose on the core. Insertion of the wedge 22 takes up this looseness. 70 For the purposes of the present invention, the wedge

22 is shorter than the tube 18 and is forced into an axially central position with respect to the tube 18 so that room is left for insulation to flow in at 21. The leading edge of the wedge is tapered to facilitate insertion, a 45° beveling from one face to the other having been found satisfactory.

Flowing insulation along edges of laminations

Although theoretically a spacer similar to the wedge 22 could be provided along the edges of the laminations, this would necessitate that the turns of wire be lengthened. It would also reduce the total amount of space provided for the coil by the apertures through the laminations where maximum dimensions place a limiting factor upon the space which can be provided.

However, in the case of the edges of the laminations, space for the flowed insulation portions 21 can be provided in an even more simple manner. It is merely necessary to provide notches 23, approximately as seen best in Fig. 2, while stamping out the laminations. Once the stamping dies are produced for this shape, the provision of these notches represents no extra cost. Now when the wedges draw the tube 18 snugly around the core 14, the notches 23 will leave a space under the ends of the tubes 18 into which the insulating material may flow.

From the foregoing, it is seen that without any extra cost insulating portions 21 are provided extending all around the central core 14, between it and the tube 18. Thus there is formed, in effect, an insulating sleeve integral with the main body of insulation 19, and extending in under the ends of the tube 18 far enough so that the minimum surface distance along it between coil 13 and laminations 12 is at least as great as and preferably considerably greater than the minimum acceptable creepage distance.

As a matter of fact if, as is commonly the case, the tube 18 is slightly longer axially than the coil 13, the minimum creepage distance will be increased by the amount that the tube 18 projects beyond the coil 13.

To be sure that there is no interruption in the sleeve 21 anywhere around the periphery of the central core portion 14, the width of the wedge 22 is preferably at least equal to the spacing between notches 23, measured transversely of the core portion 14. In practice, the wedges would usually be made very close to the full width of the main core portion 14.

I claim:

1. An electromagnetic structure including a core of magnetic and conductive material, a coil surrounding said core, a tube between the coil and the core formed of an insulating material, and of approximately the same length along the core as is the coil, and molded insulation along the ends of the coil and tube and overlapping the ends of the tube lengthwise of the core to lengthen the path of current flow along the face of the molded insulation from the coil to the core, said core being notched

5 to receive the overlapping portion of the molded insulation and that points between the notches, lengthwise of the core, extending approximately as close to the coil as the thickness of the tube.

2. An electromagnetic structure including a core formed of a stack of laminations of magnetic and conductive material, a coil surrounding said core, a tube between the coil and the core formed of an insulating material, molded insulation along the ends of the coil and tube and overlapping the ends of the tube between the tube and the core lengthwise of the core to lengthen the path of current flow along the surface of the molded insulation from the coil to the core, the laminations of said core being notched at their edges to receive the overlapping portion of the molded insulation and extending closer to the coil at points between the notches than at the bottoms of the notches, and spacing members shorter than the tube and positioned intermediate its ends and between it and the stack of laminations along the faces 15 of the stack formed by the faces of laminations to space the ends of the tube from said faces to receive the overlapping portion of the molded insulation, the overlapping portion of the molded insulation extending into each end of the tube forming a sleeve completely surrounding the core within the tube.

3. An electromagnetic structure including a core of magnetic and conductive material, a coil surrounding said core, a tube between the coil and the core formed of an insulating material, and insulation along the ends of the coil and tube and overlapping the ends of the tube lengthwise of the core to lengthen the path of current flow along the face of the insulation from the coil to the core, said core being notched to receive the overlapping portion of the insulation and at points between the notches, lengthwise of the core, extending approximately as close to the coil as the thickness of the tube; said insulation at each end of the coil extending integrally along the coil face and between the tube and the core 30 entirely around the core and having a natural shape for exact intimate surface contact with both the core and the tube.
